(57) **CLAIM**

The ornamental design for a corner device for a floor covering, as shown and described.

DESCRIPTION

FIG. 1 is an environmental perspective view of a corner device for a floor covering, shown attached to an environmental floor covering;

FIG. 2 is a bottom plan view thereof;

FIG. 3 is a top plan view thereof;

FIG. 4 is a rear view thereof;

FIG. 5 is a front view thereof;

FIG. 6 is a bottom plan view thereof, shown affixed to an environmental disk; and,

FIG. 7 is a top plan view thereof, shown affixed to an environmental disk.

The broken lines in the drawings depict environment of the corner device that forms no part of the claim.

1 Claim, 6 Drawing Sheets
